UNITED STATES PATENT OFFICE

JOSEPH SWALLOW, OF BERWYN, ILLINOIS, ASSIGNOR TO TEMPLE CORPORATION, OF CHICAGO, ILLINOIS, A CORPORATION OF DELAWARE

SOUND EMITTING DEVICE

Application filed May 27, 1929. Serial No. 366,438.

My invention relates to sound emitting devices, and particularly to reproducing units adapted to be employed in connection with loud speakers, or the like.

5 The invention has among its other objects the production of devices of the kind described that are durable, efficient and simple in construction.

10 A particular object of the invention is to provide an improved reproducing unit of the type in which an armature is employed.

A preferred form of the invention is embodied in a reproducing unit comprising a diaphragm which is operatively connected to 15 a movable armature positioned within a winding, the winding being adapted to be subjected to telephonic currents. Improved means comprising a relatively flexible and resilient strip of metal is provided for 20 mounting the armature.

Many other objects and advantages will appear as this description progresses, reference being had to the accompanying drawing, wherein:

25 Figure 1 is a rear elevation of a reproducing unit which embodies my invention;

Fig. 2 is a section taken on line 2—2 of Fig. 1;

Fig. 3 is a detailed view of an armature and 30 an armature-carrying member which form parts of the improved unit shown in Figs. 1 and 2.

Fig. 4 is a section taken on line 4—4 of Fig. 3, and

Fig. 5 is a section taken on line 5—5 of Fig. 3.

Referring to the drawing wherein I have shown a reproducing unit which embodies a 40 preferred form of the invention, reference character 10 designates a housing member provided with the usual neck 11, whereby the reproducing unit may be operatively connected to a loud speaker, or the like. A ring 45 12 riveted to the housing member 10 clamps the marginal edge of a diaphragm 15 to the housing member 10. The central portion of the diaphragm 15 is connected to an armature 16 by a pin 17, the armature 16 being 50 positioned within an armature-carrying

member 18 that is preferably formed from non-magnetic material.

As best shown in Figs. 3, 4 and 5, the armature carrying member comprises a back plate 20, side plates 21 which are formed integral with the back plate 20 and inwardly turned flanges 22 formed integral with the side plates 21. The armature 16 is positioned between the back plate 20 and the flanges 22, and is secured to the flanges 22 by a strip 23 which is preferably formed from relatively flexible or resilient material and extends transversely of the armature. As best shown in Figs. 3 and 4, the strip 23 is preferably formed with a plurality of lugs 25 60 which are soldered to the armature 16. The ends of the strip 23 are notched to receive the flanges 22 and are preferably soldered thereto, although any other suitable means may be employed for securing the strip to the flanges, if it is so desired.

Disposed around the armature-carrying member 18 is a winding 25 which may be subjected to telephonic currents, or the like, from a radio-receiving set, or the equivalent. 75 The winding 25 is disposed between pole pieces 27 and 28 provided upon a permanent magnet 30 which is secured to the ring 12 by bolts 32.

The operation of the above described device is substantially as follows: The winding 25 is subjected to a telephonic current derived from any suitable source, and this causes the armature 16 to vibrate, which vibrations are transmitted to the diaphragm 15 and translated into sound.

A feature of my improved construction is the provision of the strip 23 to mount the armature 16 in the armature-carrying member 18. Heretofore various devices have been 90 employed for this purpose, but I have found that much breakage resulted from other constructions. When wires, etc. are employed to hold the armatures in the armature-carrying members, the wires tend to work loose 95 in the solder whereby the armatures are secured to the armature-carrying members, and the armatures then produce rattling noises during the operation of the speaker. I have found that by employing a strip of 100

metal substantially as described above for securing the armature to the armature-carrying member, the strip may be soldered to the armature-carrying member and to the 5 armature in such manner that it will not work itself free.

While I have shown and described certain embodiments of my invention, it is to be understood that it is capable of many modifications. 10 Changes, therefore, in the construction and arrangement may be made without departing from the spirit and scope of the invention as disclosed in the appended claims, in which it is my intention to claim 15 all novelty inherent in my invention as broadly as possible, in view of the prior art.

What I regard as new, and desire to secure by Letters Patent, is:

A device of the kind described comprising 20 a diaphragm, a winding, an armature-carrying member within said winding, said armature-carrying member being formed from sheet metal and being provided with inturned flanges, an armature disposed within 25 said armature-carrying member, a strip of metal extending transversely of said carrying member and said armature and extending in a plane normal to said inturned flanges, the ends of said strip of metal being 30 soldered to said flanges and said strip of metal being provided with integral lugs extending at right angles from it, said lugs being soldered to said armature, and means 35 operatively connecting said armature with said diaphragm.

In witness whereof, I have hereunto set my hand and affixed my seal, this 17th day of May, 1929.

JOSEPH SWALLOW.
